UNITED STATES PATENT OFFICE.

JOHN W. COWELL, OF CHICAGO, ILLINOIS.

SCREW-HOLDING DEVICE.

1,212,743.

Specification of Letters Patent. Patented Jan. 16, 1917.

Application filed January 14, 1916. Serial No. 72,125.

To all whom it may concern:

Be it known that I, JOHN W. COWELL, a citizen of the United States, residing at Chicago, in the county of Cook and State 5 of Illinois, have invented certain new and useful Improvements in Screw-Holding Devices; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in removable screw-holding devices to be used on various forms of screw drivers and consists of a simple and efficient device of this nature so arranged that the head of a screw may be clamped and held while being set, the jaws being thrown automatically out of the path of the free end of the screw-driver for use in turning 25 the screw.

The invention consists of a simple and efficient device of this nature having various details of construction, combinations and arrangements of parts which will be 30 hereinafter fully described, shown in the accompanying drawings and then specifically defined in the appended claim.

My invention is illustrated in the accompanying drawings, in which:

35 Figure 1 is a side elevation of the device. Fig. 2 is a longitudinal sectional view. Fig. 3 is a side elevation. Fig. 4 is a sectional view on line 4-4 of Fig. 1. Fig. 5 is a detail perspective of one of the concaved 40 hinged fingers, and Fig. 6 is a detail view of the blank which, when bent, forms the disk and arms having jaws at the ends thereof.

Reference now being had to the details 45 of the drawings by letter, A designates the shank portion of a screw driver and B is a plate which is bent to form two arms K with the portion intermediate the arms apertured as at B' to receive the shank portion A, said arms terminating in screw engaging jaws E. Said arms have contracted 50 portions midway their lengths, the opposite

edges being inclined toward the contracted portions. A disk J is provided with a central slot J' for the reception of the screw 55 driver and said disk has oppositely disposed recesses N' in the marginal edge thereof, the walls of the recesses having offsets N adapted to receive said arms K. The disk is provided with oppositely disposed slots 60 for the reception of the contracted ends N² of the members O, which contracted portions N² are bent to form rolls and have pivotal connection with the slots, as shown. A coiled spring R is interposed between the 65 slotted portion of the bar K and the outer inclined convexed surfaces of the members O and serves to normally hold the jaws a slight distance rearward of the forward 70 free end of the screw driver.

The operation of my invention will be readily understood and is as follows: When it is desired to hold a screw for setting the same, the collar may be pushed forward, causing the jaws to move in advance of the 75 free end of the screw driver and, as the claw B moves forward, the arms of the jaws being at slight angles to each other, will cause the jaws to open to receive the head of the screw, the tapering portion of 80 the head of the screw being held against the concaved surface of the jaws. The spring will then tend to hold the screw against the jaws while the screw is being set. When the screw is turned, the jaws 85 will draw back behind the forward free end of the screw driver, allowing the end of the same to project sufficiently to be utilized for turning the screw in the usual 90 manner.

By the provision of a removable screw holding device embodying the features of my invention, it will be noted that, as the fingers are hinged, they will act freely and may be shaped to fit closely about the blade, 95 and preferably roughened or corrugated on the inside to more easily fasten to the blade when the spring is pushed ahead, and it will be noted that the more the claw is pushed forward the tighter the spring will 100 press upon the tongue.

What I claim to be new is:—

A removable screw driver attachment, comprising a collar having a pair of pro-

jecting screw engaging arms, a slotted disk through which the shank portion of the screw driver and said arms are adapted to pass, hinged fingers upon said disks projecting toward the collar, and a coiled spring about said fingers and designed to bear against the collar.

In testimony whereof I hereunto affix my signature in presence of two witnesses.

JOHN W. COWELL.

Witnesses:

ELIAS TOBIAS,

EMIL R. ROSENTHAL.
